2 Claims. (Cl. 230—116)

The present invention relates to improvements in portable spray devices and, more particularly, to motor/blower units for devices of the type which are designed to be carried upon the back of a person for prolonged spraying of fluids.

While it has been proposed heretofore to provide a sprayer device transportable on the back of an individual for dispensing insecticides and other crop-treating agents and, in general, for the distribution of gases, liquids, powders and aerosols at locations remote from stationary sources of power and mobile units of large size, such devices, when provided with a prime mover, did not find widespread use as a consequence of several structural disadvantages. In general, they were provided with lightweight, internal-combustion engines and pumps or compressors coupled therewith, both elements of the devices being mounted upon a carrying frame or packboard adapted to be strapped to the back of the user. Since the relatively small engines thus provided required ignition means for their operation, the magneto, high-tension coil, condenser and breaker points were commonly provided on a support plate at the rearmost part of the engine, especially since the breaker points had to be disposed at an accessible location to permit adjustment and drying when necessary. In conventional devices, the blower means were disposed proximal to the support frame while the motor or engine, with its cylinder, was spaced axially rearwardly therefrom, the magneto and other parts of the ignition means being provided at the rearmost part of the shaft. Since the magneto comprises, as is customary, a field magnet, forming a stationary element together with its yoke or core, while other magnetic means (e.g. a permanent magnet forming the movable element) was provided on the shaft, the considerable weight of the ignition system was concentrated at the maximum distance from the support frame and thus was effective with a large torque moment in tending to pull the frame rearwardly from the shoulders of the user. Not only was this arrangement highly uncomfortable, but spraying efficiencies were reduced manifold as a consequence of the inability of the person using the apparatus to maintain it on his back for prolonged periods. Furthermore, when the magneto had one of its magnetic elements mounted directly upon the shaft, the low relative speed of the magnetic elements was frequently incapable of generating the high potential required for energizing the spark plug.

It is an object of the present invention to provide an engine/blower arrangement, particularly adapted for use with portable spraying devices, wherein the aforementioned disadvantages are avoided.

Another object of my invention is to provide, in a system of this type, means for eliminating the inconvenience of a large moment of force as a consequence of the location of at least the massive portions of the ignition means at a position remote from the carrying frame or support.

Yet another object of this invention is to provide a motor/blower arrangement having an improved ignition system.

The above and other objects, which will become apparent hereinafter, are attained in accordance with the

2

present invention by providing an internal-combustion engine having an output shaft and fluid-displacing means mounted upon this shaft with an ignition system wherein the magneto elements are mounted upon the rotor associated with the fluid-displacing means. Thus it is possible to eliminate the considerable moment of force deriving from the weight of the magneto elements by disposing them close to or within the blower which is generally provided proximal to the back of the individual carrying the device. Advantageously, the fluid-displacement means comprises an impeller-type rotor, forming a flywheel for the motor, received in the blower housing, at least part of the magneto means of the ignition system being mounted in this housing.

15 According to another feature of this invention, the costs and weight involved in disposing the magneto in the blower housing can be reduced by providing at least one of the magneto elements (e.g. a permanent magnet) upon the rotary member and affixing the other of these elements 20 (e.g. the field magnet and/or its core) upon this housing in radial alignment with the permanent magnet. In this manner the conventional flywheel and/or magnetic wheel is rendered superfluous and the entire assembly can be constructed with smaller axial dimensions than the known 25 devices.

30 Still another feature of the present invention resides in the retention of the breaker points upon the motor shaft at a location remote from the blower, since these breaker points generally have an insignificant weight, even when 35 their cam is considered, and are thus disposed in a highly accessible location for service. The connection between the field coil and the breaker points in an engine system of the type described is usually a low-tension conductor so that losses are avoided. The high-tension winding of 40 the magneto can be connected directly to the spark plug or plugs of the engine. It should be noted that it is preferred to use a two-cycle engine for this purpose, the fuel being admixed with lubricating oil prior to introduction into the engine. The motor/blower assembly can be mounted upon a carrying device of the type described in the commonly assigned copending application Ser. No. 289,859 filed concurrently herewith by Heinz Schmierer.

45 The above and other objects, features and advantages 45 of the present invention will become more readily apparent from the following description, reference being made to the appended drawing in which:

50 FIG. 1 is a rear-elevational view of a spray device incorporating a motor/blower arrangement according to the present invention;

55 FIG. 2 is a side-elevational view, partly in axial cross-section, showing the motor/blower unit in greater detail; and

60 FIG. 3 is a diagram showing an ignition system suitable for use with this unit.

65 In FIGS. 1 and 2 there is shown a portable spray device adapted to be mounted upon the back of the user and comprising a support frame 10, of the type described in the aforementioned copending application, integrally formed with a receptacle 11 for the liquid to be dispensed and, advantageously, a tank 12 for supplying fuel to the engine 3 via a suitable fuel line not shown. The frame can include a pair of lateral supports 13 between which a plate 14 is provided, suitable webs 15 reinforcing the junction between the receptacle 11, the tank 12 and the carrying plate 14. It will be apparent that, for comfort, the carrying frame should be provided with a curvature about a generally vertical axis so as to fit snugly against the back of the user and, advantageously, a curvature about a horizontal axis so that the tanks rest against the shoulder region of the wearer. Suitable straps,

not further described but known per se, are provided to secure the carrying frame to the shoulder of the user. The motor/blower unit, as previously mentioned, comprises an internal-combustion engine 3, which is here shown to be of the one-cylinder, two-cycle type, mounted via flanges 3' on the rear plate 1' of a blower housing 1 which, in turn, can be formed with lugs 1" for connection to pedestals integrally formed on the carrying frame 10 via the usual bolts and, if desired, resilient feet. The blower housing 1 is so mounted that its axial intake opening 1a is spaced from the carrying plate 14 to permit induction of air into the interior of the blower whence this air can be displaced by an impeller 2 mounted upon the output shaft 3" of engine 3. This impeller shaft functions as a flywheel for the engine and may have an annular portion 2' which can be a ring integral with but rearwardly of the impeller disk 2" carrying the radial vanes or blades 2a.

The ignition system of this engine comprises, according to the invention, the usual spark plug 3a and a magneto field coil 6 which is mounted upon the blower housing 1 and at least partly received therein. The pole piece 7 of this field coil extends radially in closely spaced relationship with the impeller 2, which is provided with a permanent magnet 4 (FIGS. 2 and 3) adapted to generate the ignition pulse, the field coil 6 being connected to the spark plug 3a of engine cylinder 9 by means of the ignition cable 8. Since this magneto arrangement 4, 6, 7 comprises a moving element relatively remote from the axis of rotation of the shaft 3", the peripheral speed of the permanent magnet 4 may be such that additional voltage-increasing means can be dispensed with. If desired, however, the motor shaft 3" can be provided, at its extremity remote from the blower, with the usual breaker points in an accessible and removable housing 16. To counterbalance the permanent magnet 4, ring 2' also is provided with a counterweight 5 diametrically opposite this magnet 4.

The tangential outlet 17 of the blower housing 1 can be provided with suitable conduit means 18 connected with the tube carrying fluid from the receptacle 11 provided upon frame 10 to the conventional spray head. It will be apparent that this arrangement brings the weight of the magneto 4, 6, 7 proximal to the back of the user and markedly reduces the moment of force caused by its weight. Since the breaker points and the condenser, if any is required, are of relatively little weight, they can be accessible by removal of a cap on the rear housing 16 of the engine.

In FIG. 3 I show the breaker points 19, 20 contained within housing 16 and controlled by a cam 21 mounted upon shaft 3" in the usual manner. In this case, the field coil 6 can be constituted by a high-tension winding 6' connected to the spark plug 3a and a low-tension winding 6" connected with the breaker points 19, 20. A

capacitor 22, which can be mounted either in the blower casing 1 together with the magneto yoke 7 or within casing 16, is connected between this low-tension winding and ground. Another cable 23 is then provided to connect this low-tension winding 6" to the breaker points in casing 16.

The invention described and illustrated is believed to admit of many modifications within the ability of persons skilled in the art, all such modifications being considered within the spirit and scope of the appended claims.

I claim:

1. In a portable spraying apparatus, in combination, housing means adapted to be carried upon the back of an operator and provided with a compartment having a major dimension generally parallel to the back of said operator, said housing means being provided with an inlet open to the atmosphere for induction of air; outlet means on said housing means for connecting said compartment to a spraying device; a blower impeller journaled in said housing means and disposed within said compartment for rotation about an axis perpendicular to said major dimension, said blower impeller including a disk lying generally in a plane parallel to the back of said operator and formed with blade means along an axial side of said disk proximal to said operator; an internal-combustion engine mounted on said housing means rearwardly of said compartment and provided with a shaft coupled with said impeller; and ignition means for operating said engine, said ignition means including a magneto magnet mounted on said disk at a side thereof axially opposite the first-mentioned side and remote from said operator, field-magnet means mounted on said housing means adjacent the path of said magneto magnet between said engine and said blade means for generating an ignition pulse, a spark plug on said engine, and breaker-contact means mounted on said engine on a side thereof axially opposite said disk and connected with said field-magnet means while being actuated by said shaft for firing said spark plug.

2. The combination defined in claim 1 wherein said disk has a generally cylindrical step of relatively small diameter provided with said magneto magnet, and a step of relatively large diameter carrying said blade means, further comprising counterweight means on the first-mentioned step diametrically opposite said magneto magnet for balancing same.
